PACKAGE STACKER

Harry M. Cross, Rochester, N. Y.

Application December 9, 1944, Serial No. 567,383

2 Claims. (Cl. 198—158)

This invention relates to package stackers, and particularly to that type of mechanism that is built on a self-contained, portable base which may be placed in a selected position in a warehouse or stockroom, connected with a source of power, thereby being set in motion to carry articles up to one or more stations where they may be picked off and piled. The mechanism may be reversed to permit articles lifted from a pile to be brought down to near floor level where they may be manually removed from the machine.

The stacker is designed to run continuously while in use for the above operations. The essential parts of the device comprise an endless chain which follows a path in a flat plane; a series of brackets or package lifters attached to the chain at spaced intervals; and a power drive capable of moving the chain and lifters in two directions of travel. The frame and associated parts are preferably of standard structural steel shapes.

One object of the invention is the provision of a stacker as above outlined which is inexpensive and durable, safe to operate, and which may be conveniently moved about. A second object is to insure that packages placed in the stacker will remain upright until removed.

Another object is to provide a mechanism of this character that may tipped or tilted to permit it to pass through an ordinary door. A further object is to provide mechanism adapted to be operated by unskilled labor. Other objects will appear hereinafter.

The drawings herewith illustrate a preferred form of the invention, and in these drawings:

Fig. 1 is a front elevation of a stacker embodying the novel features of the invention;

Fig. 2 is a side elevation of Fig. 1, parts being removed;

Fig. 3 is a horizontal section at line 3—3 of Fig. 2, on an enlarged scale;

Fig. 4 is a side elevation of the stacker head shaft; and

Fig. 5 is a plan section of a detail of the chain guide.

The structure is shown herewith as made up of structural steel members, the base proper being of angles 10, 11, preferably welded together to constitute a rectangular frame, which may have casters 12 for easy movement on a floor. Upright side piers 13 of channel section carry a cross-shaft or trunnion 14 on which the entire working assembly may be tilted, as indicated by dotted lines in Fig. 2, to reduce the overall height

so that the stacker may be moved through the usual factory door opening.

A second pair of angles 15 carries the angle sub-frame members 16 and the guides 17, the latter being as long as may be required. It should be noted that for different height limits the same base, pintle and drive mechanism may be used, guides 17 and associated parts merely being made longer or shorter as required.

Near the top of the guides 17 cross-members 18 are fixed (Fig. 4), these preferably being reinforced by stiffeners 19. A plate 20, welded to the upper member 18 carries long studs 21 which pass through a shaft 22. This shaft therefore is non-rotative, and a sprocket 23 free to turn thereon is, in effect, an idler over which passes an endless chain 24, the lower part of the chain passing around the underside of another sprocket 25, which is keyed or otherwise fixed to a driven shaft 26. Sprocket 25 thus acts as a driver for the chain 24. The shaft 26 may revolve in pillow blocks or other suitable bearings 27 that are fastened to a heavy transverse angle 28 welded to the main side members 15. The long studs 21 are provided with lock nuts 21a on both top and bottom of shaft 22 and the plate 20, so that an adjustment of the upper sprocket 23 may be readily obtained for taking up slack or stretch in chain 24. When the chain is stretched beyond a certain point, the screws 21 may be backed down sufficiently to permit the removal of one chain link, and then the screws may be readjusted to level the shaft 22 and place the chain under correct tension.

The carrier chain 24 is actuated by a motor 30, which, through a self-aligning coupling 31, may drive a suitable reduction gearing 32, and the end sprocket 33 of the latter may, through a chain 34, drive a large sprocket 35 that is fixed to the lower shaft 26 to which main driving sprocket 25 is keyed. The motor is mounted on a transverse member 130 welded to the tiltable side members 15. A suitable control switch 36 may be provided whereby, through reversal of the motor, the chain 24 may be caused to travel in either direction, or the motor speed may be varied.

The package lifters before mentioned include stirrup-shaped plates 40 that are fastened to brackets or hangers of substantially the form of an L, which have their lower arms 41 at a slight angle from horizontal. The vertical arm 42 of each L bracket is pivoted at 43 on a single stud extending forwardly from one chain link pin, and such pins are provided at suitably spaced inter-

vals throughout the length of chain 24. It is obvious that the brackets 41—42, which are preferably of cast metal, constitute pendulum-like carriers, and are therefore always suspended in an upright position from their respective pivots 43 so that the packages (one being indicated at P in Fig. 2) are unlikely to become dislodged when placed in the receptacle plates 40, particularly because of the pendulum effect of the whole, and also because of the backward slope of the arms 41 toward the chain 24.

To insure a minimum of friction which might cause the pendulum supports to drag laterally, as they ride past the centers of the upper or lower sprockets and thus tilt from the vertical, a narrow ridge 44 is cast near the bottom of arm 42. This ridge projects rearwardly and acts as a line or point bearing against the front faces of angles 17 and of guards or cover plates G that are fixed in place as a safety precaution to prevent a user from becoming caught in the chains or sprockets when loading or unloading packages or articles.

To further lessen the drag or friction of the moving parts, each pivot pin 43 is provided with a beveled washer or spacer 45 (Fig. 5) which bears against the rear edges of the front arms of the angle uprights 17. As these washers are free to rotate on said pivots, friction is reduced, and furthermore the chain and the lifters are caused to ride without noticeable vibration or jerky movements.

To maintain the structure in a working position a counterweight W is attached to the lower ends of angles 17, and is so proportioned that after the working parts are tilted as aforesaid and then released, they automatically will assume a normal relation immediately. Suitable stop lugs 46 may be located on the angle base pieces 11 to define the position of the upright members 17.

It has been found desirable for some services to have the whole working structure tilted rearwardly in its operating position, to an angle of 2 or 3 degrees from the vertical. The stop lugs 46 may be adjusted as required to accomplish this condition, although such adjustment is not indicated in the drawings.

Although the device as illustrated herewith indicates a preferred form of the invention, and one that has proven practical in use, it is obvious that it is capable of considerable modification. It is intended, therefore, that the invention shall encompass any and all structures capable of fulfilling the functions above set forth, so long as such structures properly fall within the terminology and scope of the following claims.

10 I claim:

15 1. A device of the class described comprising in combination, a base, a horizontal trunnion mounted on the base, a substantially rectangular elongated frame mounted on said trunnion, a counterweight on the lower portion of said frame tending to retain the latter upright, an endless chain, a driving and a driven sprocket for said chain, means to adjust one of said sprockets on said frame whereby the chain may be adjusted, driving means including suitable gearing connected with said driving sprocket, and a plurality of package-supporting carriers spaced at intervals on and movable with the chain, said carriers being mounted in the manner of pendulums so that they remain substantially upright regardless of their position on the chain while the entire device is in normal operation and also movable parallel to the plane of the sprockets as may be required in operation.

20 20 2. A package stacker comprising, in combination, a base, posts mounted on the base, a horizontal trunnion extending between said posts, a normally upright counterweighted frame pivotally mounted on said trunnion, sprockets revolvably mounted on the frame adjacent the ends of the latter, driving means connected with one sprocket, an endless chain passing over both sprockets, and package carriers attached to brackets of substantially L-shape, said brackets being hung in the manner of pendulums on spaced pintles in said chain, whereby all the brackets tend to remain in a package-receiving position regardless of the direction of travel of the chain but are freely movable from said position as required in operation of the stacker.
